GAS OPERATED STARTING MECHANISM

Nicolas Herzmark, Paris, France

Application June 13, 1938, Serial No. 213,525
In Great Britain December 8, 1937

8 Claims. (Cl. 123—183)

This invention relates to gas-operated piston mechanism to be employed for the starting of internal combustion engines and other analogous purposes, utilizing combustible or explosive cartridges for generating gases under pressure.

The invention has for an object to provide improved means for the ignition of the gas-generating cartridge by low tension electric current such as can be obtained from automobile batteries.

A further object of the invention is to provide improved means for the application of the gas-generating cartridge to the operation of piston mechanism, for example in the starting of internal combustion engines by piston devices operated by gas pressure, and to enable a succession of cartridges to be loaded and fired without danger, if the engine fails to start at the first attempt.

Other objects and novel features of the present invention will appear from the following description of a preferred embodiment, reference being had therein to the accompanying drawings, in which:

Fig. 1 represents in part-sectional elevation a gas-operated engine starter.

Fig. 2 is a part-sectional elevation of the "pistol" or cartridge-firing device adapted to generate the gases for operating the engine starter, the section being taken on the line 2—2 of Fig. 4. Fig. 2a is an elevation of the cartridge-supporting cradle shown incompletely in Fig. 2.

Fig. 3 represents in perspective view one form of the improved cartridge.

Fig. 4 is an end view of the pistol shown in Fig. 2, the body being partly in section.

Fig. 5 is a part-sectional elevation corresponding to Fig. 2, but showing the cartridge enclosed in the combustion chamber.

Fig. 6 is a detail, in section on a larger scale, of the heating plug mounted in the movable breech-bolt of the pistol.

Fig. 7 is a diagram of electrical connections for the heating plug circuit.

Fig. 8 represents a pressure-time graph showing the rise and fall of pressure in the engine starter at the explosion of two successive cartridges.

Referring to Fig. 1, the engine starter shown is of the kind described in my U. S. A. Patent No. 1,538,700, dated May 19, 1925, and illustrated in Figs. 3 and 4 of the patent specification, from which the following description is abstracted with slight alterations:

One piston *a* is secured to a screw *b* which is

hollowed out internally; a second piston *g* is secured to a sleeve *d*, carrying at its adjacent end a nut *d*² in which the screw *b* is engaged. The pistons *a* and *g* are guided in an air-tight manner within a stationary cylinder *h* having an inlet port *h*¹ through which the gases can be admitted to the space between the two pistons. The piston *a* is revoluble within the cylinder *h* but can move longitudinally therein only to a small extent, just sufficient to shift a coupling or jaw clutch *b*³ which is mounted on a shaft *b*² secured to the screw *b*, into engagement with a driving pin *c*¹ on the engine shaft *c*. During this advance of the piston *a*, the screw *b* works through the threads of the nut *d*², while the boss *a*¹ on the outer face of the piston enters a central hole in the stationary end-plate *a*². The sleeve *d* is prevented from revolving in one direction relatively to the fixed cylinder *h* by means of longitudinal grooves *d*³ formed on its outer surface, and by feathers *i* secured within a ring *i*¹ provided with ratchet teeth *i*² engaging with corresponding teeth *h*² carried by the cylinder *h*. These ratchet teeth are inclined in such a way that they allow the ring *i*¹ to revolve in one direction but oppose its rotation in the other direction. A spring *k* bearing against a cover *l* screwed upon the cylinder *h* tends to maintain the ratchet teeth *h*² and *i*² in constant engagement. A coiled spring *m* located inside the screw *b* is attached at one extremity to the piston end of this screw and at its other extremity to a cross pin *d*¹ upon the sleeve *d*, thus tending to maintain the two pistons *a* and *g* constantly in contact. The cylinder cover *l* is provided internally with a throat or groove *l*¹, within which, when the apparatus is at rest, there is engaged a plate spring *d*⁶ carried by the sleeve *d* and so shaped that it is necessary to exert a certain force in order to displace the sleeve *d* either inwards or outwards.

Gas under pressure being admitted at the inlet port *h*¹ between the two pistons, first pushes along the piston *a* which is fast to the screw *b* thereby causing the latter to screw through the nut *d*²; this piston revolves with the shaft *b*², advancing to an extent just sufficient to bring the jaw clutch *b*³ carried by the shaft *b*² into engagement with the engine shaft *c*. Hereafter the piston *g* in its turn moves endwise with the sleeve *d* and nut *d*²; but since the sleeve *d* cannot revolve in relation to the cylinder *h* because the ratchet teeth *i*² *h*² oppose the tendency of the ring *i*¹ to revolve in the direction of the threads on the screw *b*, the sleeve merely

travels longitudinally and causes the screw *b* to rotate, which thus turns the engine shaft *c*. When the admission of compressed gas ceases, the two pistons *a* and *g* resume their initial position under the action of the spring *m*, the jaw clutch *b* being disengaged from the pin *c*.

The gas for operating the starter is generated in a pistol or cartridge-firing device shown in Figs. 2, 4 and 5, utilizing a cartridge such as 10 illustrated in Fig. 3. Referring to Figs. 2, 4 and 5, the pistol comprises a body 10, having at one end a flange 11 by which it can be secured to a convenient support; inside the body 10, there is provided a combustion chamber 12 fitted with 15 a liner 15 having its outer surface formed with longitudinal notches 16 to allow gas to pass from one end of the chamber to the other by way of these notches. A diffuser plate 17 fitted at the inner end of the chamber 12 is provided 20 with a plurality of holes 18 giving access from the chamber into a convergent outlet passage 19 leading to a union 20 for the attachment of a pipe 21, which conveys gas pressure to the inlet port *h* of the starter shown in Fig. 1. In order 25 to allow the loading of the pistol with a cartridge 22, such as shown in Fig. 3, the combustion chamber 12 opens out into a breech chamber 23 having a movable breech bolt 24 operated by a handle 25, the bolt 24 being provided 30 with helical lugs 26 which engage with corresponding lugs 27 at the sides of the breech-chamber for locking the breech in closed position in the manner well-known in the art of breech-loading firearms. When the breech-chamber is opened by raising the handle 25 to 35 disengage the lugs and then slid backwards to the position shown in Fig. 2, a cylindrical cartridge such as 22 (Fig. 3) can be dropped into place in the breech chamber 23, so as to lie between the bolt 24 and the open end of the combustion chamber 12, being supported in this position by a cradle 28 carried by a lever 29 pivoted at 30 (Fig. 2a); forward movement of the bolt then pushes the cartridge along the cradle 45 28 until its front end enters the combustion chamber, the cradle being forced downwards due to the engagement of its lever 29 by the bevelled edge of the advancing bolt. At the same time, a conical-ended plug 31 mounted in the front 50 face of the bolt engages in a central bore 32 of the cartridge, so that the latter is maintained in axial alignment with the chamber 12; when the cartridge is fully home in the chamber and pressing against the diffuser plate 17, the bolt is 55 rotated by turning down the handle 25 so as to lock the breech bolt by the co-operating lugs 26, 27, the bolt then occupying the position of Fig. 5 and the handle 25 the position shown in dotted lines at 25a in Fig. 4.

60 The forward movement of the breech bolt 24, in depressing the cradle 28, causes the lever 29 to lift its rear end after the bolt has moved sufficient to clear this end 33 of the lever, which then projects up behind the bolt, as seen in Fig. 5; on 65 the return movement, the bolt acts to depress the rear end of the lever 29, thus returning the cradle 28 to the position shown in Fig. 2.

The combustion chamber 12 has a lateral port 34 communicating with a longitudinal passage 70 35 formed in the body 10, this passage enclosing a valve stem 36 carrying a valve head 37 normally seated upon a bevelled facing 38 at a restricted part of the passage; the rear extremity of this valve stem is secured to a bridge piece 75 39 which in turn is secured to a plunger 40 car-

rying a push button 41 at its outer end, a spring 42 within this button acting to return the plunger and close the valve, as seen in Fig. 5. A transverse duct 43 connects the restricted part of the passage 35 to another longitudinal passage 44 5 to which a discharge pipe 45 is connected by a union 46; in the open position of the valve 37 (see Fig. 2), the combustion chamber is thus in communication with the discharge pipe. The bridge 39 is slotted at 47 to receive the stem 48 10 of a latch 49 movable in a direction radial of the breech chamber 23, this latch being normally held outwards by one of the lugs 26 upon the breech bolt 24, in the position of Fig. 2, or by the breech bolt 24 itself as the latter advances towards the position of Fig. 5, but being adapted 15 to slide inwards and engage in a notch 50 at the rear of the bolt 24 when the latter is closed, as shown in Fig. 5. The sliding movement of the latch is controlled by the bridge 39, the upper and lower faces of the latter being formed with notches having oppositely directed bevelled ends 51, 52 respectively, which engage with the adjacent faces of the latch 49 and of a head 53 at the outer end of the latch stem 48. The bevelled surface 51 acts to force the latch into the notch 50, when the bolt 24 is closed (see Fig. 5), the valve 37 then sealing the escape duct 43; the bevelled face 52 acts to force the latch out of the notch 50 when the button 41 is pushed inwards, this operation being therefore necessary before the breech can be opened, so that if pressure still remains in the chamber 12 a warning is given by the rush of gas through the discharge pipe 45 which may be connected to a 30 whistle or other suitable signal.

The passage 35, which is in constant communication with the combustion chamber 12 by way of the port 34, whether or not the valve 37 is open, is also connected by a duct 54 to a 40 safety device which allows the gases to escape to the atmosphere in the event of excessive pressure developing in the combustion chamber, due for example to blockage of the outlet passage 19 or pipe 21. This safety device comprises a thin 45 metal disc 55 secured by an apertured cap nut 56 in a plug 57 which is mounted in a cavity 58 on the underside of the body 10, the duct 54 leading into the bottom of this cavity so that the gas pressure will act upon the inner face of the disc 55; the aperture 59 in the cap nut 56 ensures that the disc is subjected to atmospheric pressure on its outer face, and the disc is so constructed that it will fracture if the internal gas pressure exceeds the value calculated to be safe 55 for the other parts of the apparatus. A broken disc can be replaced by removing the cap nut 56 and fitting a fresh disc in place of the broken one.

As shown more clearly in Fig. 5, the cartridge 60 22 is provided with a plurality of parallel holes 60 equally spaced apart and around the central bore 32, these holes extending from end to end of the cartridge and being for instance six in number and of the same diameter as the central 65 hole. The cartridge shown is more fully described and claimed in my continuing patent application Serial No. 244,292 filed December 6, 1938.

Fig. 6 illustrates the construction of the igniting plug 31 carried by the breech bolt 24; as there shown, the heating plug comprises a metal tube or barrel 61 adapted to be screwed into the movable breech bolt 24, the tube being formed with a bevelled collar 62 seating in a correspond- 70 75 75

ingly bevelled hole in the front wall 63 of the bolt, and having its rear end formed with screw threads 64 engaging in a correspondingly screwed hole in the rear wall 63a of the bolt, so that the tube is mounted tightly in place. The inner or forward end of the tube terminates in a thin conical wall 65 having a small central hole 66, the wall 65 being of tapering thickness so that the hole 66 resembles a circular knife-edge. An electrode passes axially through the tube 61, the stem 67 of the electrode being surrounded by insulating material, such as magnesia, filling the space within the tube 61, as indicated at 68, and the inner or front end of the electrode stem 10 forms a head 69 which fits tightly within the sharp-edged hole 66 in the conical wall 65. The electrode is thus insulated from the outer tube 61 except at the head 69, where it contacts with the edge of the hole 66, and may be welded thereto; the other end of the electrode stem passes out through a porcelain or like insulator 70 at the outer end of the tube 61 and is secured by a nut 71, beyond which there is secured an electrical contact disc 72 having its periphery notched at 73.

The contact disc 72 is adapted to be engaged by a contact plunger 74 working in an insulating bush 75 mounted in the wall of the breech chamber 23, at the side of the pistol, as shown in Fig. 4; the plunger 74 is operated by a press button 76, the movement of which is limited by a shoulder 77 so that the plunger 74 can engage the periphery of the disc 72 at its extreme outer edge, but is unable to make contact with the bottom of the notch 73. The position of the notch in relation to the rotary locking movement of the breech bolt is such that the notch lies on the side towards the contact plunger 74 until the bolt has been locked by turning down the handle 25; consequently the plunger cannot make contact with the disc unless the breech is properly closed and locked.

Fig. 7 shows suitable electrical connections for enabling the electrode of the igniting plug to be connected with a suitable source of current 78, such as a 6-volt automobile battery, under the control of the switch contacts 72, 74 operated by the press-button 76 at the side of the pistol; the passage of current will heat up the head 69 and thin conical wall 65 of the plug device, the production of heat being concentrated in the resistance formed by the thin wall and its knife edge in contact with the electrode head; the heat is thus transmitted by the plug directly to the central part of the cartridge, the combustion starting when the electrode head reaches a temperature of 180° C., for example. Due to the outward development of the combustion, the generation of gases begins relatively slowly, but when the combustion extends to the ring of holes 60 in the cartridge, the ignited surface increases rapidly with a correspondingly accelerated generation of gas until the whole of the cartridge is consumed. The slow initial generation and accelerated later generation obtained by this form of cartridge will be particularly advantageous in the application of the gas pressure to the starting of internal combustion engines by gas-operated starters such as that shown in Fig. 1. As can be seen from Fig. 8 the varying pressure developed when employing the present invention for starting a multi-cylinder explosion engine by means of a starter of the kind described, will be represented graphically by an approximately horizontal line 79 (at-

mospheric pressure) with a gradual rise of pressure at 80 for the engagement of the jaw clutch 5, the pressure then rising more steeply at 81 with a number of steps or slight declines 82 at successively higher values, these steps representing the effect of overcoming the compression in the several cylinders of the engine, until the gradually increasing pressure succeeds in starting the engine or until the cartridge is completely burnt, when the curve of pressure at 83 will 10 slowly fall back to the atmospheric line 79. It will be understood that after the firing of each cartridge, the bolt 24 has to be unlatched by operation of the push button 41 so as to discharge any residual pressure in the chamber 12 before 15 the breech can be opened to insert another cartridge; thus all danger of injury to the operator by premature opening of the breech is obviated.

In addition to starting explosion engines, the invention can be employed for generating gases to be used for operating piston mechanism of other kinds, for example reciprocating pumps and piston devices actuating oil-break electrical switches. 20

What I claim is:

1. A gas generator for the operation of piston mechanism, comprising a combustion chamber, one end of said combustion chamber being connected to a gas outlet, said combustion chamber adapted to receive an explosive cartridge, a breech chamber extending from the other end of said combustion chamber, a movable member guided in said breech chamber and adapted to feed an explosive cartridge axially from said breech chamber into said combustion chamber and to seal the end of said combustion chamber remote from said gas outlet, a heating plug mounted on said movable member, said heating plug adapted to engage said cartridge when fed 40 into said combustion chamber, and electrical means for heating said plug to cause ignition of said cartridge within said combustion chamber.

2. A gas generator for the operation of piston mechanism comprising a combustion chamber adapted to receive an explosive cartridge and having an outlet for the gases produced by combustion of said cartridge, a breech bolt movable axially in line with said chamber for feeding a 50 cartridge into said chamber, said breech bolt being rotatable through a part-revolution for locking in relation to said chamber after feeding a cartridge thereinto, a heating plug mounted centrally at the end of said breech bolt adjacent to said chamber, said heating plug adapted to engage a hole in the cartridge for centering it in relation to said chamber during the axial movement of said breech bolt, and electrical means for heating said plug to cause ignition of said cartridge within said chamber. 55

3. A gas generator for the operation of piston mechanism, comprising a combustion chamber adapted to receive an explosive cartridge and having an outlet for the gases produced by combustion of said cartridge, a breech bolt movable axially in line with said chamber for feeding a cartridge into said chamber, said breech bolt being rotatable through a part-revolution for locking in relation to said chamber after feeding a cartridge thereinto, a heating plug mounted centrally at the end of said breech bolt adjacent to said chamber, said heating plug adapted to engage a hole in the cartridge for centering it in relation to said chamber during the 70 75

- axial movement of said breech bolt, and electrical means for heating said plug to cause ignition of said cartridge within said chamber, said electrical means including a safety switch controlled by the rotation of said breech bolt.
4. A gas generator for the operation of piston mechanism, comprising a combustion chamber adapted to receive an explosive cartridge and having an outlet for the gases produced by combustion of said cartridge, a breech bolt movable axially in line with said chamber for feeding a cartridge into said chamber, said breech bolt being rotatable through a part-revolution for locking in relation to said chamber after feeding a cartridge thereinto, means for latching said breech bolt in locked position, a heating plug mounted on said breech bolt for igniting the cartridge within said chamber, and means for unlatching said breech bolt to permit its rotation in reverse direction, said unlatching means including a valve for discharge of gas pressure from said chamber.
5. A gas generator for the operation of piston mechanism, comprising a combustion chamber adapted to receive an explosive cartridge and having an outlet for the gases produced by combustion of said cartridge, a breech bolt movable axially in line with said chamber for feeding a cartridge into said chamber, said breech bolt being rotatable through a part-revolution for locking in relation to said chamber after feeding a cartridge thereinto, a heating plug mounted on said breech bolt for igniting the cartridge within said chamber, electrical means for heating said plug, a manually operable contact member, and a rotary contact member carried by said breech bolt, said manual and rotary contact members being included in the circuit of said electrical heating means and being engageable to complete said circuit only in the locked position of said breech bolt.
6. A gas generator for the operation of piston mechanism, comprising a combustion chamber, one end of said combustion chamber being connected to a gas outlet, said combustion chamber being adapted to receive an explosive cartridge, means for feeding an explosive cartridge

into said combustion chamber and thereafter sealing the end of said combustion chamber remote from said outlet, electrical means for igniting said cartridge within said combustion chamber, and safety means to prevent inverse operation of said feeding means to unseal said combustion chamber while pressure remains in said combustion chamber.

7. A gas generator for the operation of piston mechanism, comprising a combustion chamber, one end of said combustion chamber being connected to a gas outlet, said combustion chamber being adapted to receive an explosive cartridge, means for feeding an explosive cartridge into said combustion chamber and thereafter sealing the end of said combustion chamber remote from said outlet, electrical means for igniting said cartridge within said combustion chamber, a latch adapted to engage said feeding means after the sealing of said combustion chamber, manual means for disengaging said latch, a valve actuated by said manual means, and a signal operated by residual pressure in said combustion chamber at the actuation of said valve by attempted manual disengagement of said latch.

8. A gas generator for the operation of piston mechanism, comprising a combustion chamber, one end of said combustion chamber being connected to a gas outlet, said combustion chamber adapted to receive an explosive cartridge, a breech chamber extending coaxially from the other end of said combustion chamber, a member movable axially within said breech chamber and adapted to engage an explosive cartridge for feeding said cartridge from said breech chamber into said combustion chamber, a cradle adapted to support an explosive cartridge within said breech chamber for engagement by said movable member, said cradle being displaced by axial movement of said movable member after engagement of said cartridge by said movable member and partial entrance of said cartridge into said combustion chamber, and electrical means for igniting said cartridge within said combustion chamber.

NICOLAS HERZMARK.
